top depression or catch stop 41 provides a yieldable holding means for the pin 42. This positioning of the handle 45 as to the strap 46 and the slot 44 locates the pin 42 at the bottom of the slots 35, so that as the feathering stroke from Fig. 2 is completed and down pressure is exerted on the hand lever 21, 24, the paddle is given a 90° turn away from feathering initially in the short down-riding of the shaft 29 which brings the pin 42 to the upper ends of the slots 35, where the paddle shaft is held by the pin 42 for flatwise back swing in forward propulsion action on the boat 1. The complementary threading 37, 38, mounting the sleeve 36 in the housing 14, accommodates this angular control.

For the boat operator to effect backing of the boat, or rearward propulsion, it is only necessary that the handle 45 be shifted from its left extreme position (Fig. 3), to the right for catch 48 to become effective. At this position, with the pin 42 at the bottom of the slots 35, the paddle 33 is flatwise as to the direction of the boat, and down stroke of the handle 21, 24, at once rocks the paddle 90° for feathering. With the paddle thus shifted away from the boat stern, the up-stroke of the hand lever 21, 24, first shifts the paddle away from feathering to flatwise toward the boat stern in pulling the boat aft. The under side of the handle loop 45 is in the form of a spring leaf 49, affording more firm holding for the handle 45 as shifted from forward to reverse.

With the paddle 33 located in a feathering position, it is an effective rudder, even if other propulsion means be in use. Additionally steering may be taken into account in the propulsion, whether forward or rearward, by loosening the wingnut 10, if there is to be adjustment, while if for a fixed circular course, there may be tightening of the set screw 10 for the desired angle of travel in the arc. While there may normally be considered maximum advantage for over-stern location of this mechanical movement propulsion unit and control, anchoring of such at a desired position on a gunwale, of either side may be had, or even in multiple for on opposite sides as a substitute for oars. The pivot bolt 8 provides range for the paddle to be swung fore and aft from a boat side, with the handle not very much outboard.

The adjustable assembly of the projecting portions from the housing, as for the hand lever and paddle, are to parts thus readily removed, allowing for compact handling of the unit for transport to and from the boat location where desired to be installed.

The general tubular construction features contribute to weight lightness of the unit, and such may go further by adopting aluminum or magnesium as the metal. The enclosing of the lever mounting and the swivel transmission together with the control therefor in the housing, responds to ready lubrication with absence of exposure of connections between relatively movable parts and occasion for hurting an operator as well as

avoiding having apparel or other matter becoming snarled therewith.

The transmission connections and control as disclosed are quiet in operation. This in many instances is of importance in efficient angling operations.

It is to be noted that the feathering, or change of effective relation of the paddle to the housing, in practice is obtained independent of any spring. In the first place the paddle 33 is just slightly off-center or balance as to the mounting shaft 31 therefor, and this, coupled with the resistance of the water, at once there is reverse operation direction instituted therefor, causes the paddle to shift, as from paddle effecting position to feathering position. In the set-up as disclosed, when the control handle 45 is set for boat forward travel, then thrusting of the handle 21, 24, to its up position serves to hold the paddle in feathering plane. As so held, it serves as an effective rudder, and with the wing nut 10 loosened, the steering direction may be carried out in the direction desired. When the control handle 45 is set for reverse, then the up-limit for the handle 21, 24, holds the paddle 33 against feathering. Accordingly, as so submerged, there is effective braking or stopping for the boat. With the area for the paddle 33 taken as equivalent of a normal pair of oars, there is available effective boat control, not only for stopping, but in propulsion for forward, reverse, and elected angle of steering.

What is claimed and it is desired to secure by Letters Patent is:

1. A boat propulsion unit comprising a support adapted to be fixed to a boat, a frame, there being a hinge mounting the frame on the support, a second class lever having a fulcrum in and connected to the frame, the lever extending past the hinge to protrude from the frame and there form a handle for applying power to the lever, and a paddle below the frame, there being a shaft rising from the paddle and extending into the frame with a pivotal connection to the lever, said pivotal connection locating a load for the lever between the handle and the fulcrum, said hinge and fulcrum being axially parallel.

2. The unit of claim 1 wherein there is a releasable clamp included in the support, said clamp being spaced from the hinge on the side of the hinge remote from the fulcrum.
